Specification for Design.

Patented Aug. 30, 1921.

Application filed November 1, 1920. Serial No. 421,180. Term of patent 14 years.

To all whom it may concern:

Be it known that I, OTTO REINERT, a citizen of the United States of America, residing at 2928 Sullivan avenue, in the city of St. Louis and State of Missouri, have invented a new, original, and ornamental Design for a Vegetable-Cutter, in which—

Fig. 2 is a rear elevation of the same.

I claim:

The ornamental design for a vegetable cutter, as shown.

In testimony whereof, I have signed my name to this specification.

OTTO REINERT.
